ARTIFICIAL LEG.

APPLICATION FILED FEB. 9, 1903.

NO MODEL.

FIG. I

FIG. 17.

FIG. 16.

FIG. 3. *ghe*

The diagram shows a mechanical assembly consisting of a vertical stack of rectangular blocks. The top block is labeled 'J-3' and the bottom block is labeled 'J-i'. A circular component is attached to the side of the stack between the two labeled blocks.

UNITED STATES PATENT OFFICE.

CHANCY A. FREES, OF NEW YORK, N. Y.

ARTIFICIAL LEG.

SPECIFICATION forming part of Letters Patent No. 742,853, dated November 3, 1903.

Application filed February 9, 1903. Serial No. 142,464. (No model.)

To all whom it may concern:

Be it known that I, CHANCY A. FREES, a citizen of the United States, residing at New York city, Manhattan, county and State of New York, have invented certain new and useful Improvements in Artificial Legs, of which the following is a specification.

This invention relates to various improvements in artificial legs by which strength, freedom of motion, and comfort to the wearer are insured.

In the accompanying drawings, Figure 1 is a side view, partly in section, of my improved artificial leg; Fig. 2, a rear view, partly in section, thereof; Fig. 3, a longitudinal section of the ankle-joint; Fig. 3^a, a detail of the ankle-joint barrel; Fig. 4, an end view of Fig. 3. Figs. 5 to 11 are details of the joint between thigh-bar and leg-bar. Figs. 12 to 14 are details of the heel-tendon anchorage. Fig. 15 is a detail of the toe-spring with the sack partly broken away; Fig. 16, a perspective view of the ankle-block, and Fig. 17 a detail of the stump-socket.

The letter *a* represents the lower leg proper, *c* the foot, and *b* the intervening ankle-piece, of an artificial leg. The ankle-joint between leg *a* and ankle-piece *b* is illustrated more fully in Figs. 3, 3^a, and 4, such joint serving also for connecting the ankle-piece to the foot. The joint is composed of a transverse barrel *d*, having a lower bearing from end to end in a corresponding socket *b* of ankle-piece *b*, and an upper bearing in a socket *a'* of leg *a*. The barrel *d* is secured to leg *a* by a pair of upwardly-extending bolts *d'*, carrying nuts *d*². Within the hollow of the barrel and between the bolts *d'* is contained a cylindrical plug *d*³, around which the barrel is rotatable. From the plug depends a fork *d*⁴, which projects downwardly through a transverse slot *d*⁵ of barrel *d*. The fork is provided with an upwardly-extending screw-pin *d*¹⁰, that engages a threaded socket or perforation of plug *d*³, and thus intimately connects the fork with the plug, so that they will rotate together. From the fork is suspended a bolt *d*⁷ by a pivot *d*⁶, extending at right angles to the axis of barrel *d*, the bolt *d*⁷ serving to attach the joint to the foot *c* by a nut *d*⁸. It will be seen that by fitting

the plug *d*³ within the hollow of barrel *d* the entire length of the latter may be supported upon its bearing, so that superior strength of 55 the joint is obtained. Any axial displacement of the barrel within its bearings is prevented by a pair of circumferential bulges *d*⁹ on the barrel engaging corresponding grooves *b*² of socket *b*.

The ankle-piece *b* is adapted to rock laterally upon the foot *c* by means of a longitudinally-arranged semitubular journal *e*, secured to the ankle-piece *b* and rolling within the corresponding bearing *e'* of foot *c*. The 65 journal *e* is provided with an enlargement or head *e*², which is received by a corresponding depression of bearing *e'* and prevents axial displacement.

The lower forward end of the leg *a* is overlapped by a curved plate or guard *f*, projecting upwardly from the ankle-piece *b* and within which the leg is free to rock. The guard *f* is arranged concentric to the ankle-joint *d* *d*³ and at a distance in front of the 75 same. It is rigidly connected to the ankle-piece and disconnected entirely from the leg or foot, so that the leg may rock back and forth beneath the guard, while the leg and ankle-piece may rock laterally on the foot. 80 A second plate *f'* is fitted upon the top of ankle-piece *b* between guard *f* and barrel *d*, the plates *f* *f'* serving to reinforce the ankle-piece. The top plate *f'* serves, further, as an abutment for the leg proper, which prevents 85 contact between ankle-piece and leg, and thus reduces wear of the parts.

The toe *g* is composed of a pad of felt or other resilient material, which is cemented to the foot *c*. Longitudinally through the toe-pad extends a slit which is open at either one or both ends, the drawings showing it closed in front and open at the back. Within the slit is placed a flat spring *h*, surrounded by a flexible envelop or sack *h'*, the parts *h* and *h'* being attached at their rear end to the foot *c* by a screw *h*², which passes through the rear of toe *g*. By the construction described the spring is surrounded on all sides by the flexible pad and is thus effectively protected. 95 Should the spring break, however, all of its parts may be simultaneously withdrawn from the pad by pulling out the sack *h'*, which encloses and assembles the same.

i represents the heel-tendon, secured to the leg by hook *i'* and passing through the ankle-piece *b* and foot *c*. The lower end of tendon *i* is doubled around a pin *j*, which has a bearing at *j'* within the lower flange *j*² of a tubular collar *j*³, through which the tendon *i* passes. The flange *j*² of collar *j*³ bears against a corresponding offset of foot *c* above the heel-pad *c'*. The construction described insures a superior anchorage of great strength for the lower end of the heel-tendon.

* Figs. 5 to 11 illustrate the construction of the joint between the thigh-bar *k* and the leg-bar *l*. The upper end of the leg-bar is slotted vertically, as at *l'*, to form a pair of cheeks *l*². These cheeks are perforated, as at *l*³, to form the bearings for the pivot *M*, which connects the thigh-bar to the leg-bar and which is rotatable in its bearings. The pivot is of peculiar construction, being provided with a central transverse slot of a depth to extend beyond the axis of the pivot. Thus there are formed two disks *m*, connected at their periphery by a bridge *m'*, each of the disks being received by one of the bearings *l*³. The slot *m*² of the pivot is of the same width as the slot *l'* of the leg-bar *l*, so that such slots register with one another. Through the slots *l'* *m*² projects the lower end of the thigh-bar *k*, which is rigidly attached to the pivot *M* by a pin *n*, passing through perforations of disks *m* and through a perforation *k'* of the thigh-bar *k*. The lower edge *k*³ of the thigh-bar abuts against the bridge *m'* of pivot *M* and prevents independent movement between thigh-bar and pivot. A nose *k*² on the thigh-bar, which is adapted to contact with the base of slot *l'*, forms a stop-hinge for limiting the play of the joint in the forward direction. It will be seen that by the construction described a solid bearing is formed for the entire length of the pivot *M* and that an enlarged contact-surface for the joint is obtained.

Fig. 17 illustrates the socket *o*, that projects into the hollow of leg *a* and is adapted for the reception of the stump. This socket has an upper flange *o'* projecting over the upper edge of leg *a*. Between the leg *a* and the flange *o'* is interposed an annular flexible gasket *o''*, which takes up any sudden jars or jolts in walking, and thus increases the comfort of the wearer.

What I claim is—

1. In an artificial leg, the combination of an ankle-piece, with a rotatable slotted barrel supported thereon, means for securing the barrel to the leg proper, a perforated plug within the barrel, a fork having a screw-pin that engages the plug-perforation, and a bolt pivoted to the fork, substantially as specified.

2. In an artificial leg, the combination of an ankle-piece, with a leg proper, an intervening joint, a top plate on the ankle-piece in front of the joint that forms an abutment for the leg proper, and an upwardly-extending curved guard on the ankle-piece which overlaps the leg proper, substantially as specified.

3. An artificial leg provided with a foot, a longitudinally-slitted flexible toe-pad, an envelop removable within the toe-pad slit, a spring within the envelop, and a screw which connects the rear end of the spring to the foot, substantially as specified.

4. An artificial leg provided with a slotted perforated leg-bar, a slotted pivot rotatable therein, and a thigh-bar connected to said pivot, substantially as specified.

Signed by me at New York city, (Manhattan,) New York, this 7th day of February, 1903.

CHANCY A. FREES.
